(57) **CLAIM**

The ornamental design for a beverage bottle, as shown and described.

DESCRIPTION

FIG. 1 is a perspective view of a first embodiment of the claimed design for a beverage bottle;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of a second embodiment of the claimed design for a beverage bottle;
FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a front view of a third embodiment of the claimed design for a beverage bottle;
FIG. 16 is a rear view thereof;
FIG. 17 is a left side view thereof;
FIG. 18 is a right side view thereof;
FIG. 19 is a top view thereof; and,
FIG. 20 is a bottom view thereof.

The beverage bottle may be totally transparent or totally opaque, without departing from the claimed design.

The broken line showing of the pattern on the bottom of the beverage bottle is for environmental purposes only and forms no part of the claimed design.
